UNITED STATES PATENT OFFICE

2,329,066

ELECTRIC SWITCH MECHANISM

Carl Lantz, Brooklyn, N. Y.

Application August 25, 1939, Serial No. 291,846

6 Claims. (CL. 74—99)

This invention relates to switch mechanism, and is principally concerned with an improved construction of electric switch suitable for the operation of circuits independent of one another.

With the arrangement of parts as disclosed in Figures 1 and 2, four separate circuits may be switched on and off selectively by means of a single snap-action contact member. Moreover, the constructional features of this switch mechanism are such that they are productive of a new mode of switching operation on the basis of which many modifications may be made, suitable for the operation of more than four independent circuits.

The frame of the switch consists of the upper plate 169, the middle plate 170, and the lower plate 171; all of these three plates being held spaced apart by connecting posts, one of which is shown by reference numeral 172. To the lower plate, which is made of insulating material, are connected four separated conductor blades 173, 174, 175 and 176, from any one of which the electric current may be led to a separate circuit by way of the conductor 177, the metal plate 178 and the fulcrumed contact member 179, i. e., when the latter is swung away from its normal position in one of the four directions selected for establishing electrical contact with one of said conductor blades.

The several fulcrums on which the contact member 179 may swing are provided at four points on the underside of the middle plate 170, where conical depressions 180 (see Fig. 2) are formed for the purpose of receiving the respective upper free ends of the four upright legs 181, 182, 183 and 184 of the contact member 179. Likewise, on the upper side of the middle plate 170 conical depressions 185 are made opposite those on the underside of said plate. Into these upper conical depressions the respective ends of the legs 186 of the throw lever 187 are seated. The tension spring 188 is connected with its respective ends to the throw-lever 187 and the contact member 179 so that they are pulled toward each other by the spring which normally holds them in the position as shown in Fig. 1. From this position of the movable switch members, the spring 188 may be moved sideways in four different directions with aid of the throw-lever 187, and as a result of such motion the contact member 179 is thrown to circuit-closing position in the direction in which the spring 188 was caused to become overcentered. Outcuts 189 are provided on the middle plate 170, as shown in Fig. 1, to clear the way for the operation of the spring 188. In the top plate 169 simi-

lar outcuts 190 are made for guiding the motion of the throw-lever 187.

When operating the device, the throw-lever 187 is swung, as desired, in one of the four directions to the full extent; the upper section of the spring 188 is thus carried past two of the pivotal points of the contact member 179 hence enabling its snapping action to be effected in a circuit-closing direction. When the throw-lever is moved back to its normal position, it causes the spring 188 to throw the contact member 179 also back to normal position; another circuit may be closed thereafter by swinging the throw-lever 187 in a different direction.

Among the several objects of the invention may be noted the provision of a spring-actuated contact member, which member is so constructed and so fulcrumed in its frame that it may be reciprocally thrown with a sudden motion, from a normal position in any one of more than two directions, thus affording separate circuits to be operated selectively with a high degree of efficiency and simplicity.

Other objects, and the various features of the invention will become more readily apparent upon a detailed review of the accompanying drawing and specification together with the appended claims.

In the drawing, which shows a few modifications of the various possible embodiments of the invention,

Fig. 1 is a perspective view of the invention exemplified in the form of a hand-operated switch, showing a construction suitable for effecting independent circuit operation in at least four different circuits.

Fig. 2 is a fragmentary view, showing a detail of construction of the device of Fig. 1.

Fig. 3 is a cross-sectional view taken on line 3G—3G of Fig. 4, showing a modified frame construction of a switch mechanism similar to the construction illustrated in Fig. 1.

Fig. 4 is a front-view of Fig. 3, showing arrangement, in the front wall of the switch housing, of a plurality of tracks associated with the hand-operated member which carries the switch spring.

Similar reference characters indicate corresponding parts throughout the drawing.

The switch mechanism illustrated in Figures 3 and 4 is of a construction similar to that disclosed in Fig. 1, reference may therefore be made to the description of Fig. 1 for a full understanding of the switch operating principles embodied in the

device of the two last drawing figures which will presently be described.

The frame, adapted for the support of the electrical contact parts of the switch (see Fig. 3), consists in its main part of the closed housing 268, made of insulation material in the form of a rectangular box, best seen in Fig. 4. In each corner, on the disjoinable bottom-cover 269, is fixed a contactor blade with any one of which the snap-action member 178B may be thrown in and out of electric contact by force of the tension spring 15 when this is shifted in the desired radial direction to the extent required for effecting circuit-operation. Two of said contactor blades are shown in Fig. 3, and are indicated there by reference numerals 174B and 176B, the other two contactor blades are not shown in this drawing.

The switch housing 268 is accommodated in a U-shaped bend of the bracket 270 with which the said housing, including its bottom-cover 269, is held in assembled position with aid of the screws 271, the heads of which are adapted to respectively engage recessed edge portions of the housing 268, as shown in Fig. 4.

In order to afford the snap-action member 178B to be thrown reciprocally in four different radial directions, there are embodied in this member four spaced-apart upright legs which have their respective free ends supported on the conductor plate 272 while the member 178B is held in a central position, in a manner similarly as shown in the construction of Figs. 1 and 2. In the device of Fig. 3, the conductor plate 272 is shown held in a stationary position contiguous to the underside of the top-wall 273 of the switch housing. And on the outside of the top-wall 273 is supported a manipulating knob 274 which is provided with a hook 275 whereto the upper end of the tension spring 15 is suspended, so that when the manipulating knob 274 is shifted in a radial direction away from its central position, it enables the spring 15 to effect the throw of the member 178B in the particular direction in which the knob 274 was first shifted.

Viewing Fig. 4, there may be seen four equidistantly arranged radial slots 276, made in the top-wall 273 of the switch housing so as to permit the manipulating knob 274 to be shifted back and forth in four different directions from its central position, for the purpose of effecting circuit operation in any one of four circuits to which the device is properly connected by lead wires.

Having now particularly described and ascertained the nature of my invention, I should state in conclusion that, while the illustrated examples constitute practical embodiments of my invention, I do not desire to be restricted to the details of construction and arrangement of parts of the several constructions illustrated in the accompanying drawings, since manifestly they can be considerably varied without departure from the spirit of the invention.

I claim:

1. In a snap-action mechanism, a frame including a top-plate, a conductor plate held close to the inside of the top-plate, a plurality of fulcrum members arranged at a distance one from another on the said conductor plate, a snap-action member having a plurality of supporting members normally held in contact with said fulcrum members of the conductor plate; said snap-action member being adapted to swing on certain of said fulcrum members reciprocally depending on the direction of power imparted for the actuation of the snap-action member; a manipulating

knob supported on the outside of the top-plate, a tension spring interconnected with the manipulating knob and the snap-action member adapted to pull them towards each other, electrical contact means co-operable with the snap-action member whereby circuit-operation may be effected, and slots in the top-plate for permitting the manipulating knob with its interconnected spring to be shifted in definite directions for causing said spring to operate the snap-action member.

2. A mechanism, comprising a frame having a supporting plate, a plurality of fulcrum portions arranged respectively on the upper side and lower side of said plate, a member having a plurality of legs supported by the fulcrum portions on the underside of said plate, an operating lever having a plurality of legs supported by the fulcrum portions on the upper side of the plate, and a tension spring interconnected with the said member and the lever to normally hold them in contact with all of said fulcrum portions; said lever being adapted to be swung reciprocally in several different directions radially of its normal position for carrying said spring selectively in either one of said directions over a definite distance for effecting angular motion in said member at the instant the twisting force of the spring on the axis of said member changes from one direction to another.

3. The combination with a mechanism having a fulcrum support, a snap-action element having a plurality of spaced-apart pivotal members adapted to normally rest on said fulcrum support, means embodied with the mechanism to enable the snap-action element to swing reciprocally on certain of its pivotal members in any one of more than two angular directions, an operating member on the snap-action element disposed beneath the said fulcrum support, manually operable means adapted to be moved at will from a normal position reciprocally in any one of more than two directions, a spring operatively connected to the manually operable means and the snap-action element to enable the latter to be thrown angularly by force of the spring subsequently to priorly effected motion in the manually operable means in a selected direction to a definite extent, and means co-active with said operating member of the snap-action element to enable operativeness or in-operativeness to be effected in an adjunctive device, depending on the particular angular position to which the operating member is thrown.

4. The combination with mechanism having an operating member movable reciprocally in more than two angular directions, a fulcrum support for said member, a device manually movable reciprocally in more than two directions from a definite normal position, a support for said device, a tension spring operatively connected to the operating member and said device, the latter being adapted for angularly shifting said spring in any one of more than two directions to enable the operating member to be thrown in a predetermined direction subsequently to such shifting action, and a device having operating elements for the performance of a function; said operating elements being adapted to be controlled with the reciprocally movable member in said mechanism.

5. The combination with mechanism having an operating device adapted to be movable reciprocally in any one of more than two angular directions, a fulcrum support for said operating device, means having a support adapted to afford the last mentioned means to be moved selectively from a normal position in any one of more than

two directions reciprocally, a tension spring operatively connected to the operating device and said means; the latter being adapted for shifting said spring at will in any one of said plurality of directions to enable the operating member to be thrown subsequently to such shifting action by force of the tension spring in a definite predetermined direction, and operating elements of an adjunctive apparatus operatively associated with said operating device whereby during any one of

its reciprocal motions operativeness or inoperativeness may be effected severally in said operating elements.

6. A device as set forth in claim 3, wherein circuit-operating means is incorporated co-active with said operating member, adapted for the control of any one of several circuits with which the mechanism is interlinked.

CARL LURTZ.
